(57) **CLAIM**

The ornamental design for a “breast pump adapter”, as shown and described.

DESCRIPTION

FIG. 1 is a perspective view of one embodiment of a breast pump adapter which embodies my new and original design therefor having an overall translucent appearance; FIGS. 2 and 3 are front and rear elevational views thereof, respectively;

FIGS. 4 and 5 are right and left side elevational views thereof, respectively.

FIG. 6 is a top plan view thereof;

FIG. 7 is bottom plan view thereof;

FIG. 8 is a perspective view of another embodiment of a breast pump adapter embodying my new and original design therefor having a base ring which is opaque in appearance and a transition portion which is transparent in appearance, FIGS. 9 and 10 are front and rear elevational views thereof, respectively;

FIGS. 11 and 12 are right and left side elevational views thereof, respectively.

FIG. 13 is a top plan view thereof; and,

FIG. 14 is bottom plan view thereof.
